Primary Examiner — Karen E Eldridge Powers(74) *Attorney, Agent, or Firm* — Dorsey & Whitney LLP(57) **CLAIM**

We claim the ornamental design for a brush head for an oral cleansing device, as shown and described.

DESCRIPTION

FIG. 1 is a front isometric view of a brush head for an oral cleansing device, showing my new design.

FIG. 2 is a rear isometric view thereof.

FIG. 3 is a front elevation view thereof.

FIG. 4 is a rear elevation view thereof.

FIG. 5 is a right side elevation thereof.

FIG. 6 is a left side elevation view thereof.

FIG. 7 is a top plan view thereof; and,

FIG. 8 is a bottom plan view thereof.

The broken lines illustrate portions of a brush head for an oral cleansing device that form no part of the claimed design.

1 Claim, 4 Drawing Sheets**Related U.S. Application Data**

14/216,779, filed on Mar. 17, 2014, now Pat. No. 9,987,109.
